UNITED STATES PATENT OFFICE.

SARKIS T. ATTARIAN, OF PHILADELPHIA, PENNSYLVANIA, AND BEDROS T. ATTARIAN, OF BROOKLYN, NEW YORK.

BRUSH.

Application filed July 14, 1924. Serial No. 725,984.

To all whom it may concern:

Be it known that we, SARKIS T. ATTARIAN and BEDROS T. ATTARIAN, citizens of the United States, residing at Philadelphia, 5 and 1777 E. 17th Street, borough of Brooklyn, respectively, in the counties of Philadelphia and Kings, respectively, and States of Pennsylvania and New York, respectively, have invented new and useful Improvements 10 in Brushes, of which the following is a specification.

This invention relates to brushes, and more particularly to a fountain brush particularly designed for use by tailors, cleaners 15 or analogous artisans, and an object of the invention is to provide a brush structure which is comparatively simple in construction and comprises a plurality of compartments adapted to contain different types of 20 fluids, the outlet from which compartments are controlled by suitable plunger operated valve structures to permit the operator or user of the brush to control the flow of the particular fluid at will.

25 During the cleaning of various articles of wearing apparel or analogous material, a cleaning fluid, such as gasoline or a suitable chemical preparation, is employed and quite frequently water is used either afterwards 30 or in connection with the cleaning fluid to provide thorough cleaning of the garment; and it is an object of this invention to provide a novel, practical type of fountain brush structure by means of which two various 35 fluids may be easily, quickly and efficiently applied to the article being cleaned.

Other objects of the invention will appear in the following detail description, and in the accompanying drawings wherein:

40 Figure 1 is a side elevation of the improved brush.

Figure 2 is a longitudinal section of the improved brush.

Figure 3 is a horizontal section through 45 the brush.

Referring more particularly to the drawings, the improved brush comprises a brush back 1 which has a plurality of bristles 2 attached thereto in any approved manner.

50 The brush back 1 has end supports 3 suitably attached at its ends to its surface opposite the bristle carrying surface and it also has supports 4 attached thereto at spaced points to provide spaced pockets 4. The 55 supports 4 support containers or reservoirs

5 and 6, above the back 1, each of which have downwardly projected extensions 7 at their ends outwardly of the corresponding supports 4. The extensions 7 of one reservoir being positioned at one end of the brush, 60 while the extension of the other reservoir is placed at the opposite end of the brush. The extensions 7 have inclined partitions 8 therein in which suitable valve seats 9 are formed. Valves 10 are provided for controlling the passage of the fluid from the main bodies of the reservoirs into the spaces formed beneath the partitions 8, and the valves 10 are carried by suitable plungers 11. The plungers 11 extend slidably 70 through the tops of the reservoirs 5 and 6 and through the supports 3. Springs 13 are coiled about the plungers 11 for holding the valves 10 properly seated and thumb buttons 14 are carried by the stems of the 75 plungers to permit the unseating of the valves 10. The bottoms 15 of the extensions 7 are perforated, as shown at 16, and the perforations 16 communicate with openings 17 formed in the brush back 1 to permit the 80 fluid released from either of the compartments to pass through the brush back, and upon the bristles 2 for application to the garment. Suitable filling plugs 18 are provided to permit the filling of the tanks or 85 reservoirs 5 and 6.

It is, of course, to be understood, that the invention may be constructed in various other manners and the parts associated in different relations, and therefore, we do not 90 desire to be limited in any manner except as set forth in the claims hereunto appended.

What we claim is:

1. In a brush, a perforated brush back, bristles carried thereby, a plurality of reservoirs supported from the back in close proximity thereto, a depending extension on each of said reservoirs having a partition therein, each partition being provided with a valve seat, said depending extensions provided with openings to permit fluid to flow from the extension through certain of the bristles in the brush back, said extensions disposed at remote positions one with respect to the other whereby the fluid from the respective reservoirs will engage the bristles at remote points. 100

105 2. A brush comprising a back, bristles carried thereby, a plurality of tanks arranged in parallel relation, each tank having an 110

angularly disposed extension, the extensions being disposed at opposite ends of said back, a partition within each of said extensions, said back and extensions having sets of 5 openings in registration with each other at remote points and opening on to the bristle carrying face of said back, each partition being provided with a valve seat, a valve co-acting therewith, means for normally holding the valves in engagement with said seats, 10 and manipulating portions on the free ends of the valves for permitting manual depression of the valves.

3. A brush comprising a back having side 15 and end walls rising therefrom, spaced transverse supports provided on the top of said back to provide spaced pockets, bristles extending from the opposite face of said

back, a plurality of tanks each having an angular extension disposed in the respective 20 pockets, a partition within each of said extensions, said back being provided with sets of openings at opposite ends thereof for registration with similar sets of openings provided in the bottom walls of said extensions, each partition being provided with a valve seat, and valves for co-action respectively with the valve seats for selectively controlling the flow of liquid adapted to be contained in said tanks to the bristle side of 25 said back.

In testimony whereof we affix our signatures.

SARKIS T. ATTARIAN.
BEDROS T. ATTARIAN.
